UNITED STATES PATENT OFFICE.

ALFRED T. KRUSE, OF DEFIANCE, OHIO, ASSIGNOR TO THE AMERICAN STEEL PACKAGE COMPANY, OF DEFIANCE, OHIO, A CORPORATION OF OHIO.

SHEET-METAL PACKING-CASE.

No. 884,670.

Specification of Letters Patent.

Patented April 14, 1908.

Application filed September 20, 1906. Serial No. 335,377.

To all whom it may concern:

Be it known that I, ALFRED T. KRUSE, a citizen of the United States, residing at Defiance, in the county of Defiance and State of Ohio, have invented certain new and useful Improvements in Sheet-Metal Packing-Cases, of which the following is a specification.

The invention relates to improvements in sheet-metal packing-cases designed with particular reference to the transportation and storage of liquids contained in bottles and similar vessels.

The invention relates more particularly to the construction of the upper and lower edges of the case and means for securing and supporting the lid or cover and bottom in proper position whereby these portions of the case are greatly strengthened and rendered less liable to injury as well as improving the general construction of the case.

The invention also relates to improvements in bottoms of either the open or closed type or class, and means for securing the same to the case.

The paramount object of the invention is to provide a generally improved packing-case having either a closed or open bottom and adapted to be used either with or without a lid or cover.

With these ends in view, the invention consists in the novel construction, arrangement and combination of parts, hereinafter described, illustrated in the accompanying drawings, and particularly pointed out in the appended claims.

Referring to the accompanying drawings, forming a part of this specification, Figure 1, is a transverse sectional perspective view of an improved case embodying my invention.

Fig. 2, a detail perspective view showing a modified form of lid-supporting-flange or bar. Fig. 3, a sectional perspective view of one of the walls of the case showing manner of securing an open bottom comprising a series of bottle-supporting-bars. Fig. 4, a detail isometric view of an intermediate portion of one of the bottle-supporting bars shown in Fig. 3. Fig. 5, a similar view of the tongued end of the same before being bent over and secured about the beading at the lower edges of the case as shown in Fig. 4. Fig. 6, a detail perspective view of a modified form of bottle-supporting-bar showing manner of attachment to the lower edges of the walls of the case. Fig. 7, a similar view of the tongued

end of the same. Fig. 8, is a cross sectional view of the bar shown in Fig. 7, taken through line 8—8, of said figure.

Similar characters of reference designate like parts throughout all the figures of the drawings.

The walls 1, of the case are bent or crimped, near their upper and lower edges, to form outwardly-extending supporting-flanges 2, and 3, respectively, and the edges thereof are bent over forming upper and lower beadings 4, and 5, preferably inclosing a wire 6. The beadings 4, and 5, abut against the supporting-flanges 2, and 3, and the outer edges of the same are, preferably, flush with the outer edges of the supporting-flanges as shown.

The lower supporting-flange 3, forms a bottom-supporting flange and the lower beading 5, forms a friction-bearing strengthening-beading about the lower edges of the case, and the groove or recess provided by the upper supporting-flange 2, is adapted to form a seat for and contain one side of a strengthening lid-supporting-strip or bar 7, which may be either flat as shown in Fig. 2, or T-shaped, in cross section, as shown in Fig. 1, and, preferably, having its depending portion 7^a, secured to the walls of the case by means of rivets 8.

The lid or cover 9, has its marginal edges bent over forming a beading 10, inclosing a wire 11, and the edges of the lid or cover are adapted to rest upon said lid-supporting-strip or bar 7, with the beading 10, within and preferably flush with the beading 4, of the case thus adding to the strength of the upper edges of the case when the lid is in its closed position.

The groove or recess provided by the bottom-supporting-flange 3, is adapted to form a seat for and contain the bent over marginal edges 12, of a closed bottom 13, as shown in Fig. 1, or the ends of the bottle-supporting-bars 14, forming an open bottom as shown in Figs. 3, and 6, and hereinafter described. The edges of the closed bottom 13, are bent over and about the lower beading 5, forming a second or double friction-bearing strengthening-beading 5^a, about the lower edges of the case.

The bottle-supporting-bars 14, comprised in an open bottom case may be of any suitable and convenient form but are, preferably, U-shaped in cross section, and are preferably bent or formed out of sheet metal in either

the form shown in Figs. 6, and 7, with the depending portion 14^a, thereof flush with the friction-bearing strengthening-beading 5, of the case, or of the form shown in Figs. 3, 4, 5 and 5, in which the bars are formed by a strip of metal bent or crimped upon itself longitudinally to form the depending portion 14^a, and provided with elongated tongues 15, bent upon themselves to form an 10 end flange 16, taking into the groove or recess provided by the outwardly-extending bottom-supporting-flange 3, and are then bent over and about the friction-bearing beading 5, about the lower edges of the case 15 whereby the bars 14, are securely fastened thereto. In Figs. 6, and 7, the ends of the horizontal portion of this form of bar simply take into the groove of the bottom-supporting-flange 3, and the ends are secured to the 20 walls of the case by means of a tongue 17, taking through a slot or opening in the flange and bent over the outer edge of the same.

The ends of the depending portions 14^a, of the bars 14, may either abut against the 25 beading 5, as shown in Fig. 3, or be cut away to provide a notch or recess intermediate the ends thereof and the beading 5, as shown in Fig. 6.

The walls of the case may be formed of a 30 single blank of sheet metal bent at the corners of the case and having the meeting ends of the sheet suitably united, forming continuous encircling outwardly-extending supporting-flanges with a lid-supporting-bar 35 mounted in the upper supporting-flange, or made up of separate sheets of metal and lid-supporting-bars suitably united at the corners of the case.

The term "bottom," as used in the specification and appended claims, is used in a general sense and includes both a "closed bottom," as shown in Fig. 1, or an "open bottom," as shown in Figs. 4, and 7, *i. e.* what may be termed an integral bottom, and one 45 made up of separate bars, preferably, of the form shown and described.

From the foregoing description, taken in connection with the accompanying drawings, the construction and advantages of my 50 invention will be readily understood.

Having thus described my invention, without having attempted to set forth all the forms in which it may be made, or all the modes of its use, I declare that what I claim 55 and desire to secure by Letters Patent, is,—

1. A packing-case, consisting of suitable walls crimped to form upper and lower outwardly-extending supporting-flanges forming interior recesses and beadings abutting 60 against said supporting-flanges, a strengthening-bar mounted in the recess formed by the upper supporting-flange, and a bottom having its marginal edges taking into the recess formed by said lower supporting-flange 65 and bent about the lower beading forming a

second or double beading about the lower edges of the case.

2. In a packing-case, the combination with suitable walls crimped near the upper edges thereof to form an outwardly-extending supporting-flange providing a recess, and a beading formed above and resting on said supporting-flange; of a strengthening-bar mounted in said recess and projecting inwardly to form a lid-supporting-flange. 75

3. A packing-case, comprising suitable walls crimped near the upper and lower edges forming outwardly-extending supporting-flanges forming recesses and having the edges thereof bent over forming a beading resting 80 against said supporting-flanges, a strengthening-bar mounted in the recess formed by the upper supporting flange and extending inwardly to form a lid-supporting-flange, a bottom taking into the recess formed by the lower supporting-flange, and a beaded lid or cover mounted on said lid-supporting-flange and resting within and flush with the upper beading of the case. 85

4. In a packing-case, the combination with suitable walls crimped to form an outwardly-extending supporting-flange providing a recess, and a beading formed above said supporting-flange; of a strengthening-bar mounted in said recess and projecting inwardly to form a lid-supporting-flange, and a beaded lid or cover mounted on said lid-supporting-flange and resting within and flush with said beading formed about the upper 95 edges of the case. 100

5. In a packing-case, the combination with suitable walls crimped near the lower edges thereof to form an outwardly-extending supporting-flange providing an inner recess, and a friction-bearing beading formed below said 105 supporting-flange; of a bottom bent over near its edges forming a marginal fold taking into said recess and having its edges bent over the outside of said beading forming a double friction-bearing beading about the 110 lower edges of the case.

6. In a packing-case, the combination with suitable walls bent near the lower edges thereof to form a supporting-flange providing an inner recess, and a beading formed below 115 said supporting-flange; of a bottom taking into and secured within said inner recess and impinging against said beading.

7. In a packing-case, the combination with suitable walls bent near the lower edges thereof to form a supporting-flange providing an inner recess, and a beading formed below said supporting-flange; of an open bottom comprising bottle-supporting-bars 120 having the ends thereof taking into and secured within said inner recess and provided with depending portions flush with said beading. 125

8. In a packing-case, the combination with 130

suitable walls provided with an outwardly-extending supporting-flange providing an interior recess, and a friction-bearing beading formed below said supporting-flange; of a series of bottle-supporting-bars provided with elongated tongues bent upon themselves forming end flanges taking into said interior recess and bent over and about said friction-bearing beading.

10 9. In a packing-case, the combination with suitable walls bent to form a bottom-supporting-flange providing an inner recess, and a friction-bearing beading formed below said supporting-flange; of a series of U-shaped supporting-bars having the ends thereof taking into said interior recess and depending portions flush with said friction-bearing beading.

15 10. In a packing-case, the combination with the walls thereof bent to form a bottom-supporting-flange providing an interior recess, and a beading formed below said flange; of a series of supporting-bars, of substantially U-

shape in cross section, having the ends of the horizontal portions thereof taking into said interior recess with the ends of the depending portions abutting against said beading.

11.. A packing-case, comprising walls crimped into an outwardly-extending bottom-supporting-flange providing an inner recess and having their lower marginal edges below said flange curled over and about a wire forming an impinging friction-bearing beading, and a bottom having its marginal ends taking into said inner recess and depending portions abutting against and supported by said friction-bearing beading.

In testimony whereof I have signed my name to this specification in the presence of two subscribing witnesses.

ALFRED T. KRUSE.
